Telephone & Telegraph Company, Chicago, Ill.,
a corporation of Delaware

Application December 20, 1937, Serial No. 180,686
In Great Britain January 11, 1937

5 Claims. (Cl. 179—18)

The present invention relates to automatic switches for use in telephone or like systems and particularly electromagnetically-operated step-by-step switches of the two-directional type arranged to have all their movements controlled by two operating magnets only.

Switches of this type and particularly vertical and rotary switches have generally been arranged to have so-called rectangular motion, that is to say release is effected by the advancement of the wipers beyond the end of the bank contacts after which they fall and are then rotated back to normal under the bank by spring tension. Such a movement may not always be sufficiently rapid where the switch is required to absorb a digit and in such cases it is possible to provide speedier release by arranging for the wipers to return along the path over which they were set. In the case of digit absorption however the wipers will release from the first rotary position only while with the switch as hitherto used the wipers after completing a connection move forward clear of the bank before restoring vertically. This involves some difficulty in obtaining a tension in the restoring spring which shall be suitable for both methods of operation and the chief object of the invention is to overcome this difficulty.

According to one feature of the invention in a two-directional electromagnetically-operated step-by-step automatic switch provided with only two operating magnets and adapted to have its wipers restored to normal along the path over which they were set in response to re-operation of the primary magnet, the circuit arrangements of the magnet are such that in all circumstances the switch wipers are restored to normal by the re-operation of the primary magnet.

According to another feature of the invention in a two-directional electromagnetically-operated step-by-step automatic switch provided with only two operating magnets and adapted to have its wipers restored to normal along the path over which they were set in response to re-operation of the primary magnet, the circuit arrangements of the magnet are such that in all circumstances after the switch has been seized for use the primary and secondary magnets are operated in turn and the primary magnet is again operated before the switch is rendered available for further use.

Still another feature of the invention is that in a two-directional electromagnetically-operated step-by-step automatic switch provided with only two operating magnets and adapted to have its wipers restored to normal along the path over which they were set in response to re-operation

of the primary magnet, after a connection has been extended over the switch wipers, a circuit is completed for the primary magnet which thereupon operates to restore them to normal.

5 The invention will be better understood from the following description of one method of carrying it into effect, reference being had to the accompanying drawings comprising Figs. 1 and 2. These when arranged side by side form a circuit diagram of a so-called digit-absorbing group selector of the vertical and rotary type which has access to one or other of two sets of outlets. After the switch has been stepped vertically to a particular level, it is caused to release thereby 10 absorbing the first digit while at the same time the outgoing leads are changed over to a second set of wipers. In response to the second digit the switch again steps vertically and then hunts automatically in the rotary direction for a free outlet in the appropriate group of the second set. If the wipers are operated by the first setting 15 digit to any other level the switch functions as an ordinary group selector and hunts for a free outlet in the appropriate group of the first set. Under all release conditions the wipers are 20 restored to normal along the path over which they were set.

Considering now the circuit operation, when the calling party's loop is extended across the 25 incoming negative and positive conductors, relay A operates over its outer windings in series and at armature *a1* operates relay B which locks over armature *b2*. A guard earth is thereupon applied to the incoming P conductor by way of 30 armature *b1* whilst relay ON is operated by way of its lower winding over armature *b3*. Relay ON upon operating energises relay C over its lower winding by way of armature *on2*, contacts NR3, armature *b5* and resistance YC to battery. 35 armature *b1* whilst relay ON is operated by way of its lower winding over armature *b3*. Relay ON upon operating energises relay C over its lower winding by way of armature *on2*, contacts NR3, armature *b5* and resistance YC to battery. 40 completes a holding circuit for relay A at armatures *on3* and *on4* independently of armatures *c2* and *c3* and at armature *on5* completes a circuit to light the supervisory lamp LP which is connected to battery over common conductor 45 12 by way of equipment which is arranged to give an alarm if the switch fails to step off-normal and operate relay H within a predetermined period. Assuming that the switch is functioning as a first selector, the middle winding of relay A 50 is now connected at armature *on8* to an earthed dial tone transformer over common lead 11, so that dial tone is applied to the incoming speaking leads by induction from the middle winding of relay A to the two outer windings in order to inform the calling party that he may commence

to dial. Relay C at armature *c5* prepares the impulsive circuit for the vertical magnet VM, the magnet however being non-operative in series with relay B, while at armature *c6* relay C completes a locking circuit for itself which is independent of the vertical magnet interrupter contacts *vm*.

On reception of the first train of impulses, relay A responds and each time it releases a circuit is completed to energise the magnet VM as follows: earth, armatures *b2*, *a1* and *on1*, the low resistance upper winding of relay C in parallel with a spark quench resistance YA, armature *c5*, magnet VM to battery and accordingly the switch wipers are raised to the level corresponding to the digit dialled. During the impulse train relay B is intermittently short-circuited at armature *a1* but this relay remains operated due to the slugging effect of the short-circuiting. The presence of metal rectifier MRA in the energising circuit of relay B prevents the slowing down of the magnet operation which would otherwise result by the direct connection of a comparatively low value non-inductive resistance YB in parallel with its winding. It will be readily understood that neither the vertical magnet nor relay C will hold operated in series with relay B and moreover the inductance of the latter relay is such that it has no appreciable effect on the magnet performance.

On the first vertical step the off-normal springs are mechanically operated and at contacts *N1* relay H is operated by way of its middle winding in a circuit including armature *c6*, contacts *NP1*, *NR1* and *N1*, armature *on1* and contacts *NR2*. Relay H thereupon at armature *h1* connects its right-hand winding to the test wiper *P1*, at armature *h5* short-circuits the lower energizing winding of relay C so that the slugging effect thus produced enables relay C to hold operated during the train of impulses which intermittently energise its upper winding and at armature *h4* disconnects the lamp LP and completes a locking circuit for relay ON over its lower winding.

Assuming first that the wipers have been raised to an ordinary level, that is, a level not set aside for digit absorption, the normal post springs NP will not be operated and the switch will function as an ordinary group selector.

At the end of the impulse train, relay A remains steadily operated and maintains relay B while after a short interval relay C releases and completes an energising circuit for the rotary magnet RM as follows: earth by way of delayed alarm equipment on to the common lead 10, test jack springs *T2*, armature *on6*, rotary magnet interrupter contacts *rm*, armatures *h6* and *c4*, magnet RM to battery. The wipers are thereupon advanced into engagement with the first set of contacts in the level selected and the rotary magnet interrupter contacts are opened. The rotary off-normal springs are operated on the first rotary step and at contacts *NR1* the operation of relay ON is made dependent on armature *h4* while during the transit time of contacts *NR2* relay H remains held by way of its left-hand winding in parallel with the magnet RM before the contacts *rm* open.

If the test wiper *P1* encounters an engaged outlet, which is indicated by the presence of earth or booster battery potential, relay H will be held operated over its right-hand winding by way of armature *h1*, 11th step cam contacts *S2*, armature *da4* and the wiper *P1* and the disconnection of its original holding circuit over its left-hand

and middle windings by the interrupter contacts *rm* is therefore without effect. The rotary magnet de-energises however and on the closure of its interrupter contacts the magnet is re-energised to advance the wipers to the second set of contacts in the level selected. This stepping operation continues automatically until an idle outlet in the group is reached, or alternatively the wipers are advanced to the 11th position.

If the *P1* wiper encounters a free outlet, that is, one unmarked by earth or booster battery potential, relay H will quickly restore and at armature *h6* further opens the magnet driving circuit whilst the selected outlet is immediately busied from earth over armatures *b1*, *h5* and *da4* and the *P1* wiper. The holding circuit for relay ON is now disconnected at armature *h4* and this relay releases whereupon relay C is re-operated in the circuit: earth, interrupter contacts *vm*, normal post contacts *NP1*, lower winding of relay C, armature *on2*, rotary off-normal contacts *NR3*, armature *b5*, resistance *YC* to battery. Relay C thereupon at armatures *c2* and *c3* disconnects relay A and switches the incoming speaking leads by way of armatures *da2* and *da3* to the first set of negative and positive wipers. Relay A upon releasing at armature *a1* short-circuits relay B and during the release time of the latter relay, relay H is re-operated from earth, armatures *b2*, *a1*, *on1* and *c4*, contacts *NR2*, middle winding of relay H to battery. Meanwhile the loop extended over the negative and positive wipers operates the A and B relays in the succeeding selector, whereupon a guard earth is returned over the P lead to maintain relay H by way of its right-hand winding when relay B releases after its slow period.

In response to the dialling of the second and subsequent digits, trains of impulses are transmitted over the first set of negative and positive leads to succeeding switches to route the call to the wanted party.

If all outlets in the level selected prove busy, the wipers are rotated to the 11th position where the cam springs are mechanically operated and at contacts *S2* the holding circuit for relay H over its right-hand winding is disconnected. Relay H now releases as described previously, opens the magnet driving circuit, releases relay ON and reoperates relay C. Armatures *c2* and *c3* thereupon switch the incoming leads as before through to the negative and positive wipers, which however now connect by way of the multiplied 11th step contacts back again to the outer windings of relay A which therefore remains held over the incoming loop and maintains relay B. Cam contacts *S1* connect up the busy tone transformer over common lead 13 to the middle winding of relay A whereupon busy tone is induced in the outer windings and is applied in a balanced circuit to the incoming speaking leads. Cam contacts *S2* extend earth from armature *b1* over armature *da4* to the test wiper *P1* to operate an overflow meter which may be connected to the 11th outlet of that particular level for traffic observation purposes.

Considering now the case in which the first digit dialled raises the switch wipers to a level on which discrimination takes place, the normal post springs are mechanically operated by the switch shaft when this level is reached. On release of relay C in the normal manner, an energising circuit for the rotary magnet RM is completed at armature *c4* as before and as a result the wipers are advanced into engagement with the first out-

let. Since this particular level is set aside for absorption of the first digit, the first outlet thereon cannot be utilised and it is therefore arranged to leave the P contact associated with this particular set disconnected in order to cause the switch to be released by way of the path over which it was set. On this level therefore, since the P1 wiper encounters no potential, relay H releases in the usual manner and at armature *h6* disconnects the magnet energising circuit, while at armature *h4* relay ON is released. Owing to the opening of contacts NP1, relay C is not operated in this case and moreover a circuit is completed for the vertical magnet from earth, armature *da5*, normal post contacts NP2, armatures *b4* and *h3*, off-normal contacts N2, armature *c5*, vertical magnet to battery. The vertical magnet pawl when operated is arranged to engage with an extension arm of the rotary detent and move it out of engagement with the rotary ratchet member so as to initiate the full release of the switch along the path over which it has been set, for instance by the use of a pivoted vertical ratchet member in the manner described in British Specification No. 399,815, complete accepted Oct. 11, 1933. This arrangement reduces the release time to a minimum and enables the switch to be satisfactorily released in an interdigital period. During the release operation the vertical magnet interrupter contacts *vm* in the operated position maintain the energising circuit for the vertical magnet independently of the normal post contacts NP2 which open as soon as the switch commences to restore vertically and these contacts *vm* also ensure that relay ON is not re-operated until the switch has fully restored to normal. When this occurs, all mechanically-operated springs are restored to normal condition and hence the opening of the contacts N2 removes the short-circuit from the low resistance lower winding of relay DA and this relay now operates in series with the vertical magnet which remains held in this condition. Relay DA at armature *da1* locks over its upper winding, at armatures *da2*, *da3* and *da4* switches over the incoming leads to the second set of wipers, at armature *da6* cuts off the dial tone circuit and at armature *da5* connects earth over contacts NP1 and NR1 and armature *b3* to operate relay ON by way of its lower winding. Relay ON thereupon at armature *on2* completes a circuit for the lower winding of relay C which at armature *c5* opens the circuit of the vertical magnet VM and transfers it to the impulsive circuit in preparation for the second train of impulses.

On the dialling of the second digit, the switch steps vertically and then performs an automatic rotary search for a free outlet in the manner previously described but in this case hunting takes place over outlets in a group of the second set of lines. It will be noticed that any further operation of the normal post springs NP is made ineffective at armature *da5* and hence any digit may be dialled as the second digit.

On the release of the connection at the conclusion of conversation, earth is removed from the P conductor at the controlling succeeding switch in the train thereby releasing relay H. This relay thereupon at armature *h2* opens the holding circuit of relay C and at armature *h3* prepares an energising circuit for the vertical magnet VM. This circuit is completed on re-

lease of relay C from earth supplied to common conductor 10, test jack springs T2, armatures *b4* and *h3*, off-normal contacts N2, armature *c5*, magnet VM to battery. Accordingly in the 5 manner previously described the energisation of this magnet initiates the release of the switch along the path over which it has been set. When the switch wipers reach the normal position, the off-normal contacts N2 are again opened and disconnect the magnet energising circuit and the switch is then available for further use.

At the commencement of release a momentary unguard period on the incoming P conductor represented by the sum of the release times of 15 relays H and C is provided to enable preceding switches to restore. On the release of relay C following that of relay H, earth is applied over off-normal contacts N3 and armature *c1* to the incoming P conductor to guard against 20 seizure during release. When the switch reaches normal, contacts N3 open and remove the guarding earth thus freeing the switch for further use.

Consideration will now be given to the operation in cases where the subscriber hangs up prematurely. If this occurs during dialling, relay A maintains relay C and the vertical magnet during the release time of relay B. On release of relay B after its slow period, this circuit is 25 opened and after a further short interval relay C releases. Thereupon a self-interrupted driving circuit is completed in the normal manner for the rotary magnet RM from the earthed common conductor 10 and accordingly the 30 wipers are rotated until they encounter a free outlet or alternatively reach the 11th position when relay H releases to cut the driving circuit as previously described. On release of relay H, relay ON is released in turn while the earthed common lead 10 is extended over armatures *b4* and *h3* to energise the vertical magnet and bring about the backward release of the switch in the manner previously described. If the calling 35 party should hang up during the hunting movement, the rotary search will continue until a free outlet is encountered when relay H will release and energise the vertical magnet as before to bring about backward release of the switch. Should the subscriber hang up without dialling, 40 the vertical magnet will be energised during the release time of relay B and relays C, ON and H will also be operated. On release of relay B, relay C and the magnet VM are de-energised and on release of relay C a self-driving circuit is 45 completed for the rotary magnet RM and the circuit operation then proceeds as described above.

Should a maintenance officer desire to attend to the switch, he is able to guard it against 50 seizure during this time by short-circuiting the test jack springs T1 by means of a suitable link provided for the purpose, whilst the removal of the link from the test jack springs T2 enables him to manually step the switch vertically and 55 rotate it as desired. After the inspection or adjustment is completed, the switch may be restored to normal by the re-insertion of the link into springs T2 and then freed for further use by removal of the link from springs T1. If the switch has only been stepped vertically, the closure of the off-normal contacts N1 brings about the operation of relay ON by way of its upper winding and this relay in turn energises relay H over its middle winding. Hence on the re-insertion of the link into the springs T2, a self-in-

terrupted driving circuit is completed for the rotary magnet from the earthed lead 10 and release subsequently takes place in the manner just described. If the switch wipers have been rotated into the bank, on re-insertion of the release link since relays ON and H are already normal (their operating circuits having been broken by the operated rotary off-normal contacts NR1) the vertical magnet VM will be energised immediately to bring about the release.

A test buzzer connected to test jack springs T4 over common lead 14 and armature da1 enables the set of wipers in use to be determined without removing the dust cover from the switch.

We claim:

1. In an automatic switch for extending connections over any of a plurality of lines responsive to the receipt of impulses, wipers, means adapted to initially move said wipers to give them access to certain of said lines, means adapted to then move said wipers to select one of said certain lines, and means responsive to the seizure of said switch and the subsequent initiation of the release thereof without transmitting impulses thereto for first operating said first means, then operating said second means and finally reoperating said first means.

2. In a drop back switch, wipers having a normal position, a plurality of groups of lines accessible to said wipers, stepping means for moving said wipers to select a group of lines, a second stepping means for moving said wipers to select a line in the group thereby to enable a connection to be extended over the wipers and that line, means for automatically reoperating said first stepping means to cause the wipers to be restored to their normal position whenever a predetermined group of lines is selected, and means for also reoperating said first stepping means to cause the wipers to be restored to their normal position responsive to the release of a connection extended over said wipers.

3. In a switch wherein wipers which have a normal position and which are moved therefrom responsive to impulses comprising a first digit

sometimes extend a connection over a line of the group designated by that digit and at other times are restored to their normal position to be moved therefrom responsive to additional impulses comprising a second digit to extend a connection over a line of the group designated by the second digit, impulse operated means for moving said wipers to give them access to the lines of a particular group, means for then moving said wipers into association with a line of that group, means for at times initiating the restoration of the wipers after said first digit, and means for initiating the restoration of the wipers responsive to the release of a completed connection, said last two means effective to reoperate said impulse operated means to cause the wipers to be restored.

4. In a switch having two wiper sets and wherein responsive to the receipt of impulses comprising a certain digit a connection is extended over one wiper set and a line of the group designated by that digit and responsive to the receipt of impulses comprising a different digit followed by impulses comprising a second digit a connection is extended over the other wiper set and a line of the group designated by the second digit, impulse operated means for moving the wipers from their normal position to give them access to the lines of a particular group, means for moving the wipers into association with a line of that group, means for extending a connection over the wipers and that line, and means responsive to the release of the connection for reoperating said impulse operated means to cause the wipers to be restored to their normal position.

5. In a switch as claimed in claim 4, wherein the wipers are moved from their normal position responsive to impulses comprising either said certain digit or said other digit, means effective responsive to the receipt of impulses comprising only said certain digit for reoperating said impulse operated means to cause the wipers to be restored to their normal position.

CHARLES EDMUND BEALE.

IDRIS TREVOR RICHARDS.
